UNITED STATES PATENT OFFICE.

GEORGE H. RICKE, OF CINCINNATI, OHIO, ASSIGNOR, BY DIRECT AND MESNE ASSIGNMENTS, TO FLEXIBLE WOODEN-SOLE SHOE COMPANY, OF CINCINNATI, OHIO, A PARTNERSHIP.

SHOE.

1,159,330.

Specification of Letters Patent.

Patented Nov. 2, 1915.

Application filed July 26, 1915. Serial No. 41,963.

To all whom it may concern:

Be it known that I, GEORGE H. RICKE, a citizen of the United States, residing at the city of Cincinnati, in the county of Hamilton and State of Ohio, have invented certain new and useful Improvements in Shoes, of which the following is a specification.

My invention belongs to that class of shoes provided with a sole made from a non-flexible material, such as wood, fiber or equivalent material, but which, by reason of my unique and peculiar construction, is rendered flexible or yielding, so that it will give or bend at a given point or points; thus enabling the wearer to walk, run or stoop, the same as if the ordinary leather shoe were used by him.

Shoes of this character are to be worn by workers who stand on wet, damp floors or hard concrete floors, on damp ground, who work in places where it is impossible to use leather soled shoes, as in chemical works, dye houses and the like; by parties who are exposed to cold, damp and inclement weather. By using these shoes the feet are kept dry and warm and the health kept normal and not impaired.

My new shoes are very simple and are cheap of manufacture and highly efficient in service.

In the accompanying drawing forming part of this specification, Figure 1, is a perspective view of my new shoe, Fig. 2, is a sectional view, taken on the line 2—2 of Fig. 3, Fig. 3, is an isometric view of the two joint parts, Fig. 4, is a plan view of the sole, the upper being removed, and Fig. 5, is a side view of the joint parts in position, the sole being partly broken away at each end.

In the present instance the sole is formed of two parts, the arch and heel part 1, and the toe part 2, both made from wood and provided at their edge with a groove or cut away part 3, into which the edge of the upper 4 fits and is tacked by nails 5, but it may be otherwise attached, if desired.

Between the sole parts 1 and 2, I place or form a joint and at this point the sole bends and yields as in walking. This joint is very simple and is formed of two parts 6 and 7, the part 6 being attached to the part 2 and the part 7 being attached to the sole part 1.

The joint part 6 is provided with a forward extension 8 and the joint part 7 is

provided with an extension 9 which extends both forward and backward of the part 7. These parts 6 and 7 and their extensions are preferably made integral.

The extensions 8 and 9 are cut away or notched at their upper edges where they meet the parts 6 and 7, so that when the parts are together the upper edges of the extensions 8 and 9 will only reach to the lower level of the cut away part 3, so that the upper 4 can be properly put onto the sole parts. Part 6 has a convex face 10 and the part 7 a concave face 12 and the back of each part is straight or of any desired shape.

The part 6 fits within the rear part 7, its convex face 10 fitting into the concave face 12 of part 7, and the extensions 8 fitting inside the forward part of extension 9, the edge of the sole at each side being recessed or cut away to allow the extensions 8 and 9 to fit properly and so that the outer face of extension 9 will lie flush with the outer edge of the sole parts and form an even uninterrupted surface which will enhance the appearance of the shoe and will also hide the joint itself so that the meeting line between the parts 6 and 7 is not visible.

In the extension 8 on joint part 6, I provide holes 14 and 18 and in the forward part of the extension 9 of joint part 7, I provide hole 15 and at the rear of said extension 9, I provide a hole 16. By screws 19 passing through holes 18, I hold the joint part 6 in position and by screws 17 passing through holes 16, I hold the joint part 7 in position in the sole sections and I may hold them in place and position in any other desired manner.

When in place and fitting together between the faces of the meeting ends of the sole parts 1 and 2, the hole or eye 14 on extension 8 and the hole or eye 15 on extension 9 coincide and screws 13 are passed therethrough and into the forward or toe section 2, but any other means may be used to thus connect and fasten the parts together. This point where the screws 13 enter is a pivotal point or fulcrum on which the sole parts bend or yield to accommodate the sole to the action of the foot in walking.

The convex face 10 and concave face 12 are on a radius with the pivotal point 13 as the axis of the circle, so that, when in walking, the ball of the foot is directly over the

joint made in the shoe sole, the toe and the arch and heel section will move up and down as the foot bends, so the act of walking is followed by these parts and at the same time 5 there is no friction between the faces 10 and 12 at the juncture of the joint so there will be no wear or buckling of the leather.

Over the back of the parts 6 and 7 and over their top edges I place a leather cap or 10 hood 20, which, together with the parts 6 and 7 can be cemented or otherwise connected in place so as to be firmly positioned. This cap 20 prevents any water, liquid, moisture, debris or the like from entering and 15 passing through the joint into the shoe and thus the foot is kept in a normal state, just as in a leather shoe. I may make my hood 20 out of any other material or of any shape or contour. I dispense with the use of any 20 extraneous parts or pieces in making this joint; in fact it is made from the least possible number of parts. It will wear as it is not subject to great strain on account of its unique construction and arrangement. The 25 edges of the hood 20 may extend over and be tacked down with the lower edge of the upper 4, when it is put in place on the sole.

The sole and upper and the joint parts 30 may be made of any material desired. The parts which form the joint may be reversed on the sole sections, so that the fulcrum point will be on the rear section. However, I prefer to use the parts as set forth and shown.

35 While I have described one specific form of carrying my invention into effect, it will be readily apparent that the same is capable of considerable modification and change, without material departure from the spirit 40 and principle of the invention, and I wish to be understood as claiming that such modifications and changes will still fall within the scope of my invention.

What I claim as new and my invention 45 and desire to secure by Letters Patent is,

1. In a shoe of the character described, a sole comprising a forward section and a rear section made of non-flexible material, a joint between said sections comprising a metal 50 part having a concave face and a flange at each end and a metal part having a convex

face fitting said concave face and a flange at each end, means coöperating with the flanges on one part for securing said part to the sides of the rear sole section, means 55 coöperating with the flanges on the other part for securing said part to the sides of the forward sole section, and means coöperating with the flanges on both parts for fulcrumming the part secured to one sole sec- 60 tion to the other sole section.

2. In a shoe of the character described, a sole comprising a forward section and a rear section made of non-flexible material, a joint between said sections comprising a metal 65 part having a concave face and a flange at each end and a metal part having a convex face fitting said concave face and a flange at each end, means coöperating with the flanges on one part for securing said part to the sides of the rear sole section, means 70 coöperating with the flanges on the other part for securing said part to the sides of the forward sole section, means coöperating with the flanges on both parts for fulcrumming the part secured to one sole section to 75 the other sole section, and a cap fitting over said joint.

3. In a shoe of the character described, a sole comprising a forward section and a rear 80 section made of non-flexible material, a joint between said sections comprising a metal part having a concave face and a flange at each end and a metal part having a convex face fitting said concave face and a flange 85 at each end, means coöperating with the flanges on one part for securing said part to the sides of the rear sole section, means coöperating with the flanges on the other part for securing said part to the sides of the 90 forward sole section, and means coöperating with the flanges on both parts for fulcrumming the part secured to one sole section to the other sole section, the flanges of one joint part fitting within the flanges of the other 95 joint part at the sides of the shoe.
